UNITED STATES PATENT OFFICE.

FREDERICK H. KANNING, OF EAST ST. LOUIS, ILLINOIS.

W.RENCH.

No. 841,692.

Specification of Letters Patent.

Patented Jan. 22, 1907.

Application filed July 25, 1906. Serial No. 327,707.

To all whom it may concern:

Be it known that I, FREDERICK H. KANNING, a citizen of the United States, residing at East St. Louis, Illinois, have invented a certain new and useful Improvement in Wrenches, of which the following is a full, clear, and exact description, such as will enable others skilled in the art to which it appertains to make and use the same, reference being had to the accompanying drawings, forming part of this specification, in which—

Figure 1 is a side view of a wrench constructed in accordance with my invention. Fig. 2 is an edge view of said wrench. Fig. 3 is a sectional view taken on the line 3-3 of Fig. 1. Fig. 4 is a side view of a modified form of my invention. Fig. 5 shows a head provided with an alligator jaw, and Fig. 6 is a perspective view of one of the interchangeable jaws which is employed when it is desired to use the wrench on pipes or round articles.

This invention relates to wrenches, and particularly to wrenches of the type shown in my prior patent, No. 777,955, dated December 20, 1904.

One object of my invention is to provide a wrench having a pivoted head in which an interchangeable jaw is adjustably mounted, so that the wrench can be used on objects of various shapes and size.

Another object of my invention is to provide a wrench of the character referred to having improved means for locking the head in its adjusted position.

Referring to Figs. 1, 2, and 3 of the drawings, which represent the preferred form of my invention, 1 designates the shank or handle of the wrench, and 2 designates plates which are fastened to said shank and project beyond the upper end thereof to form arms between which the head 3 is arranged, said head being pivotally connected to said arms by a pin 4. The head 3 is provided with a rigid jaw 5 and also a coöperating adjustable jaw 6, having a curved engaging face in which teeth are formed, so that the wrench can be used for turning pipes or objects of circular shape. When it is desired to convert the wrench from a pipe-wrench into a nut-wrench, the adjustable jaw 6 can be replaced by a jaw 7, having a straight face, as in the wrench shown in Fig. 4.

Referring to Fig. 1, it will be noted that the head of the wrench is provided with a

transversely-extending groove or bore 8, which is approximately circular shape in cross-section, and mounted in said groove is the shank 9 of the adjustable jaw 5, the end of the shank 9 being screw-threaded and extending through the rigid jaw 5. The groove 8 in the head 3 is so formed that the walls thereof overhang the shank of the adjustable jaw, and thus prevent it from being displaced, and while I have herein stated that said groove is approximately circular shape in cross-section it will of course be understood that it could be formed in various ways to prevent displacement of the adjustable jaw without departing from the spirit of my invention.

A knurled nut 10 is mounted on the end of the shank 9, and said nut is confined in position by a lug 11, which projects upwardly from a laterally-extending portion 12 of the head. Preferably the groove 8 in the head of the wrench is of greater depth than the diameter of the shank 9 of the adjustable jaw, while the opening in the rigid jaw through which the threaded portion of said shank extends is of approximately the same diameter as said shank, so that the adjustable jaw can rock slightly in its bearing, and thus permit the wrench to be disengaged readily from the object on which it is used. I also prefer to provide the rigid jaw with a recess 13 (shown in dotted lines in Fig. 1) to receive the curved extension 14 at the base of the adjustable jaw, so that said jaw can be moved very close to the rigid jaw, and thus enable the wrench to be used on pipes or objects of very small diameter.

The means which I have herein shown for retaining the pivoted head 3 in adjusted position also forms one of the novel features of my invention and consists of a plunger 15, which coöperates with recesses or notches 16, formed in the periphery of the disk-shaped portion 17 of the head 3, that is arranged between the arms on the shank of the wrench. Said plunger is of non-circular shape in cross-section, as shown in Fig. 3, and is provided with a screw-threaded portion with which a knurled adjusting-nut 18 coöperates, said nut extending through openings in the plates 2, that are connected to the shank of the wrench. With a construction of this character the plunger 15 can be forced into operative position by turning the nut 18 and will be positively locked in this position until the

nut is turned in the opposite direction, thereby preventing the head from being accidentally unlocked.

In Fig. 4 I have shown a modified form of my invention in which the disk-shaped portion of the head is provided in its periphery with teeth 20, that coöperate with an adjusting-worm 21, which is journaled in bearings formed in the shank, said screw extending through openings formed in the plates 2, connected to said shank.

In both forms of my invention the disk-shaped portion of the pivoted head 3 is provided with a shoulder 22, which coöperates with a shoulder formed on the end of the shank when the head is in the position shown in full lines in Fig. 1, so as to insure a rigid bearing for the head, and thus relieve the locking-plunger from strain.

When the head is in the position shown in dotted lines in Fig. 1, the same result is accomplished by the laterally-extending portion 12 of the head which engages the edge of the shank.

In Fig. 5 I have shown a head provided with rigid jaws of the alligator type, which can be substituted for the head 3, provided with the adjustable jaw, and in Fig. 6 I have shown an interchangeable jaw, which can be substituted for the straight-face jaw when it is desired to convert the wrench from a nut-wrench to a pipe-wrench.

Having thus described my invention, what I claim as new, and desire to secure by Letters Patent, is—

1. A wrench comprising a shank provided at its upper end with a longitudinally-extending bore, plates connected to said shank and projecting beyond the upper end thereof, a head carrying jaws and having a disk-shaped portion arranged between said plates, a pin carried by said plates and extending through the disk-shaped portion of said head, a threaded plunger mounted in the bore in the shank for engaging the disk-shaped portion of the head to lock it in position, and an adjusting-nut mounted on said plunger and extending through openings in the plates; substantially as described.

2. A wrench comprising a shank having a pair of plates connected thereto and projecting beyond the upper end thereof, a movable head having a disk-shaped part arranged between the projecting portions of said plates

and pivotally connected thereto, said head being provided with a rigid jaw and an open-sided slot, an adjustable jaw having a threaded shank mounted in said slot and ex-

tending through an opening in said rigid jaw, an adjusting-nut mounted on said shank and bearing against the outer side of said rigid jaw, a laterally-extending portion 12 on the head provided with a lug 11 which holds said adjusting-nut in position, and means carried by said plates and coöperating with the disk-shaped part of the head for locking the head in its adjusted position; substantially as described.

3. A wrench comprising a shank, a pair of plates connected to said shank and projecting beyond the upper end thereof, a pivotally-mounted head arranged between said plates and provided with a straight-face rigid jaw having a recess formed at the lower end of the engaging face, a coöperating adjustable jaw carried by said head, said jaw being provided with a curved face which at its lower end merges into an extension that projects into the recess of the rigid jaws when said jaws are closed, and means carried by said plates for locking the head in position; substantially as described.

4. A wrench comprising a bifurcated shank, a head provided with a disk-shaped portion arranged in the bifurcation of said shank on a fixed pivot, a notch or shoulder formed in the periphery of said disk-shaped portion which is adapted to coöperate with a shoulder formed at one side of the upper end of the shank when the head is in one position, a laterally-extending member on said head arranged above the disk-shaped portion thereof for coöperating with the other side of the shank when the head is in a different position, and an adjustable jaw carried by the head; substantially as described.

5. A wrench comprising a shank, plates connected to the sides of the upper end of said shank, a head arranged between said plates and pivotally connected thereto, said head being provided with a rigid jaw and a disk-shaped portion through which the pivot for the head extends, a plunger mounted in a slot in the upper end of the shank for engaging the disk-shaped portion of the head to hold it in adjusted position, and an adjusting-nut mounted on a threaded portion of said plunger and extending through openings in said plates; substantially as described.

In testimony whereof I hereunto affix my signature, in the presence of two witnesses, this 20th day of July, 1906.

FREDERICK H. KANNING.
